UNITED STATES PATENT OFFICE.

REYNOLD JANNEY, OF NEW YORK, N. Y., ASSIGNOR TO THE WATERBURY TOOL COMPANY, A CORPORATION OF CONNECTICUT.

DRIVING MECHANISM.

1,254,695.

Specification of Letters Patent. Patented Jan. 29, 1918.

Application filed February 21, 1913. Serial No. 749,789.

To all whom it may concern:

Be it known that I, REYNOLD JANNEY, a citizen of the United States, residing at New York, in the county of New York and 5 State of New York, have invented certain new and useful Improvements in Driving Mechanism, of which the following is a specification.

This invention relates to driving mechanism one of the primary purposes of the invention being to provide effective means of the character noted which can be preferably controlled at will in a ready and quick manner, to obtain speed changes or variations in velocity of a member driven by said mechanism, of whatever nature said member may be. Said mechanism can be employed with advantage in many and widely-different connections and although it is of peculiar 15 importance for actuating a member which has a back and forth movement, by which I mean either what is commonly considered as a reciprocation or oscillation, it is operative in other ways. For instance said mechanism might be advantageously used for moving a part in one direction or for a portion of such movement, while independent means or gravity might be utilized to secure the return movement of said part or vice 20 versa.

In the drawings accompanying and forming part of the present specification I have represented in detail one of the several convenient forms of embodiment of the invention which to enable those skilled in the art to practise the same will be fully set forth in the following description. I can depart in radical respects from this showing within the scope of the invention defined by the 35 40 claims following said description.

Referring to said drawings:

Figure 1 is a top plan view of the lower portion of a planer or as seen from a point above the bed thereof, the uprights which 45 support the tool-carriage being in horizontal section and said planer being equipped with driving mechanism involving my invention.

Fig. 2 is a sectional side elevation of the same, the section being on the line 2—2 of 50 Fig. 1.

Fig. 3 is a vertical cross section on the line 3—3 of Fig. 2.

Fig. 4 is a top plan view of a bracket and the parts supported thereby all to be herein- 55 after more fully described.

Fig. 5 is an elevation of the parts seen in Fig. 4.

Fig. 6 is a transverse section of the parts shown in said Figs. 4 and 5.

Fig. 7 is a horizontal section on the line 60 7—7 of Fig. 6.

Figs. 8 and 9 are detail views in sectional top plan of a portion of said planer, its bed and certain coöperating parts, certain of the elements being in different positions 65 as will be hereinafter explained.

Fig. 10 is a sectional plan view of a control shaft, rack and pinion mechanism connected therewith, and a locking device for the rack, and,

Fig. 11 is a cross section on the line 11—11 of Fig. 10.

Like characters refer to like parts throughout the several views which it will be perceived are on different scales.

As already intimated my driving mechanism can be employed with advantage in many different connections it being of particular advantage when employed in conjunction with a reciprocatory or oscillatory member in that I can vary the speed of such a part on each stroke thereof. In the drawings I have shown portions of a planer and said mechanism when associated therewith is adapted to reciprocate said bed and 80 through the intervention of suitable means, vary the velocity of said bed on each of its movements. The same thing would also be so when said mechanism is combined with the reciprocatory member of a printing 85 press. There may be apparatus, however, where I would wish to secure speed changes simply on one stroke of a member, the opposite movement being independently secured, and as illustrative of two types of machines 90 of such sort I will mention a drop hammer and a pile driver. Said variable speed mechanism may be of any desirable nature, what is known as a "hydraulic variable speed gear" answers satisfactorily in this respect, 100 although as will be inferred, equivalent means might be provided. With the foregoing general statements I will now refer more in detail to the organization shown in said drawings.

As I have already stated one of the several uses to which the mechanism can be put, is for driving the reciprocatory bed of a planer and when incorporated therein said mechanism with the coöperation of suitable means, 110

will reciprocate said bed, such as that denoted in a general way by 2, the framework 3 having suitable ways on its upper side to support and guide said bed. The body portion of the framework is preferably made hollow or chambered as at 4 to receive the hydraulic variable speed gear device 5 which as already stated constitutes one suitable and also advantageous form of speed-varying means. The hydraulic variable speed gear 5 is practically a duplicate of that shown, described and claimed in Letters Patent No. 924,787 granted to me June 15, 1909, to which reference may be had for a full understanding of such a device, although the latter will be sufficiently described to show its operative connection with a member to be driven. A hydraulic variable speed gear generally comprises a driving member, such as the shaft 6, which may be actuated in any desirable manner, for example by a pulley 7 fastened thereto, and a driven member, such as the shaft 8 from which latter the power of said part 5 is usually applied to the member to be driven. In the casing of said hydraulic variable speed gear 5 is mechanism by which, through the aid of a suitable controller, the shaft 8 or some analogous member can be driven either forwardly or backwardly at different speeds. Said device 5 also has a controller, such as the shaft 9, by which the shaft 8, through the agency of the inclosed mechanism can be governed. This controller acts upon what is known as a "tilting box." Said tilting box has a neutral position and when occupying the same, the shaft 8 will be at rest or stationary. If said tilting box be moved in one direction from neutral position the shaft 8 will be driven forward while if said tilting box is moved in the opposite direction away from said neutral position the shaft 8 will be rotated oppositely, the speed of movement of said shaft 8 depending upon the position of said tilting box which as will be assumed presents one of several kinds of regulators for the shaft 8 or its equivalent. It will be understood that as the tilting box leaves its neutral position the speed of the shaft 8 is progressively increased. Said controller or shaft 9 through suitable mechanism acts on the tilting box to shift the same, and said controller or shaft 9 therefore has positions which correspond exactly with those of the tilting box. By the operation therefore of said shaft 9 the speed or direction of movement of the shaft 8, through the intermediate mechanism, can be effectually governed. It will be also clear that changes in speed and direction of movement of the shaft 8 are accomplished independently of the shaft 6 which in the construction shown is driven at a constant speed and ordinarily continuously although this is not essential in all cases. I should also explain that where the

driven member is moved only in one direction by the driving mechanism, it is not necessary that the "controller" as I have termed it, should move oppositely from its neutral position, the only necessity in this case being to regulate the amount of movement of said controller away from its neutral or ineffective position or that which it occupies when the shaft 8 or similar part, is at rest. By incasing the device 5 in the chamber 4 compactness is secured. As will be clear the variable speed transmission device of my patent comprises in its organization a variable stroke hydraulic pump, this being that part of the structure located at the left in Fig. 1 of the drawings of said patent, of the mid-plate. This variable stroke pump operates a hydraulic motor situated at the right in said Fig. 1 of said mid-plate. The parts of the construction are also shown in Fig. 23 of said patent, the mid-plate 13 dividing the two parts of the variable speed transmission device. In the art of hydraulics I might also mention that the pump is known as the A-end and the motor operated or driven thereby the B-end. In the pump or A-end is what is known as a tilting box and which is denoted by 20 in the drawings of said patent. When this stands practically vertically the pistons 31 have no endwise motion, the result being that no fluid is pumped. This is the neutral position of the tilting box. By moving the tilting box oppositely from the neutral the pistons will be reciprocated, the greater the movement of the tilting box from the neutral being followed by corresponding increase in stroke of the cylinders so as thus to increase the speed of the motor or B-end and parts driven thereby. From this description and what has already been noted, it is believed that the action of the variable speed transmission device will be fully comprehended.

The effect of the shaft 8 can be transferred to the bed 2 in any convenient manner. The mechanism shown for this purpose will now be described. Fastened to the shaft 8, is the pinion 10 in mesh with the spur gear 11 fixed to the shaft 12 on the framework of the machine, said shaft 12 rigidly carrying the pinion 13 in mesh with the spur gear 14 the shaft 15 of which is also sustained by said framework. Said spur gear 14 is in mesh with the teeth of the rack-bar 16 fastened to the underside of the bed 2. It therefore follows that on the rotation of the shaft 8 in opposite directions, said bed will, through the intermediate mechanism described, be reciprocated.

In the present case the driving mechanism is governed to change the direction of movement of said bed 2, by means operative with the latter. That is to say when said bed has practically completed its movement in one direction, it will be reversed automatically.

Said bed can be moved either fast or slow on its advancing movement and the same conditions can be secured on its retractive movement. In the organization shown the 5 changes in velocity of the bed are obtained by varying the amount of movement of the controller or shaft 9 as will hereinafter appear. If the amount of movement of said controller away from its neutral or inef- 10 feitive position be great the speed of the bed during such period of action will be rapid while if the controller be shifted but a short distance from its neutral position the bed during such time will be driven cor- 15 respondingly slower. The means for governing the position of the controller are manually-operable so that the speed of the bed can be governed at will.

Mounted on the bed 2 are actuators or 20 dogs 17 and 18 which are the devices which initially operate mechanism, by which the shaft 9 is turned in opposite directions to effect the reciprocation of said bed. Other means might of course be employed for the 25 purpose. I will now set forth the mechanism operative by these two actuators or dogs, and the connection of the same with said shaft 9 and for this purpose reference should be had to Figs. 4, 5 and 6. Fastened 30 to and extending outwardly from the framework 3 is a bracket 19 terminating at its outer end in the sleeve or hub 20, the lower portion of the tube 21 being driven into said sleeve or hub so as to be rigid or vir- 35 tually integral therewith. Said tube has a circumferential annular flange 22 bearing against the upper side of said sleeve. Extending entirely through said tube is the rock-shaft 23 which is primarily operated 40 in opposite directions by the traveling bed 2; that is to say when said bed is traveling in either direction it gives to said rock-shaft a partial movement, the remainder of the movement being effected by separate 45 means, such as a spring, which, however, is placed under tension through the prime agency of said bed. Therefore while said rock shaft is initially directly operated upon by the bed, its final action is caused indi- 50 rectly by said bed. Said rock-shaft 23 as will hereinafter appear is operatively connected with the controller or shaft 9.

Fastened to said rock-shaft 23, is the arm 24 situated between the operating projec- 55 tions 25 and 26 on the upper side of the flange 27 provided with an integral sleeve 28 oscillatory on the upper end of tube 21. The arm 24 in Fig. 4 is shown as being in contact with the projection or stud 26 against 60 which it was moved practically at the time the traveling bed 2 reached the end of its backward movement. When the bed reaches a predetermined point in its forward movement, the actuator or dog 17 will engage the 65 extension 29 of the plate or flange 27 and

will move said plate or flange therewith as the bed continues its advancing movement. At a later point as will hereinafter appear said arm 24 will strike the projection or stud 25 so that on the opposite movement 70 of said carriage the actuator or dog 18 will strike the lug 29' and return said plate or flange 27 to its original position and on such movement of said plate or flange the arm 24 is caused to move therewith by reason of 75 the engagement between said arm and the projection or stud 25. The arm 24 is therefore oscillated through the primary agency of the bed and as said arm oscillates the rock-shaft 23 is also caused to oscillate in 80 unison therewith.

The spring 30 presents a convenient means for completing the oscillations of the rock-shaft 23, said spring being shown as encircling the rod 31, bearing at its outer 85 end in the head of the T-shaped member 32, the shank of which is swiveled in the arm 33 fastened as by pinning or otherwise to the rock-shaft 23. The rod 31 fits freely within said head. The inner end of the 90 spring 30 bears against the check-nut 34 by which the tension of said spring can be regulated and which as will be understood is threaded into said rod 31 shown as provided at its inner end with the eye 35 to 95 receive the depending pin or pivot 36 of the bracket or bearing 19. As will hereinafter appear the movement of the sleeve 28, plate 27 connected therewith and rock-shaft 23 together with the parts associated therewith, is limited and the amount of such movement in each direction governs the speed of the bed 2. In Fig. 4 the parts have been arrested by one of the two stops hereinafter described.

It will be assumed that the plate 27 is being shifted by the traveling bed 2 in the manner already described and that said plate in turn is shifting the arm 24 and the parts connected therewith. On such action 110 the rod 31 is also being swung over and at the same time the spring 30 is being put under tension so that when said rod reaches a center line or has just crossed the same, the spring will be released and being under 115 tension and acting against the arm 33 will complete the movement of said rock-shaft 23. On the return movement the operation just described is reversed.

As already intimated the connections be- 120 tween the rock-shaft 23 and the control-shaft 9 may be of any desirable nature. Those illustrated will now be described. Keyed or otherwise suitably fastened to said shaft 9 is the pinion 37 in mesh with the reciprocatory rack-bar 38 (see for example Figs. 1, 8, 9, and 10), guided by suitable guiding means on the framework of the machine. To one end of said rack-bar is pivot- 125 ed the rod or link 39 connected in similar 130

fashion with the arm 40 freely pivoted upon the rock-shaft 23 (as shown best in Figs. 4 to 7.) Rigid with and pendent from the arm 33 is the pin or stud 41 which extends down 5 through an arcuate slot 42 in the arm 40 between the ends thereof, thus providing for a loose or lost motion connection between said rock-shaft 23 and control-shaft 9, said pin or stud being normally between the ends of 10 said slot which is shown as concentric with the axis of oscillation of said rock-shaft 23.

It will be supposed that the control-shaft 9 has been operated to reverse the movement of the bed 2 and that the latter is being advanced at the predetermined speed. When 15 the dog 17 strikes the extension 29, the plate 27 will be moved in a forward direction, the arm 24 and rock-shaft 23 being similarly operated. It will be understood that when the 20 arm 24 is in the position shown in Fig. 4, the spring 30 and rod 31 will stand at the angle shown in said view. On the initial forward movement of the rock-shaft 23 said rod 31 and spring 30 will be swung there- 25 with to tension said spring, so that the spring when free to act, can shift the parts rapidly. It will be clear that as the rock- shaft 23 moves forward, it carries therewith the arm 33 to effect the movement of the pin 30 41 toward the forward end of the arcuate slot 42, the latter occurring about the time that said spring 30 crosses the center line, so that said spring can forwardly shift the arm 40 which up to this point had been at 35 rest. On the opposite or backward movement of the bed 3 the operation just described is reversed. As said arm 40 is moved forward the rod 39 and hence the rack bar 38, will be advanced so that said rack bar 40 will rotate the pinion 37 and hence the shaft 9 to shift said shaft in such manner that it will cause the variable speed gear device 5 to retract the bed 2, said shaft being moved from one extreme position where it 45 is held by one manually-adjustable stop, (hereinafter described) to another extreme position where it will be held by a second manually-adjustable stop, (also hereinafter described). During the movement of said 50 shaft 9 in such opposite directions it assumes, between its extremes, its neutral position at which point the bed will be stationary.

As will be understood the mechanism between the rock-shaft 23 and the controller or control-shaft, involves a loose connection or two parts connected for relative movement which is the preferable construction although it is not necessary that the 60 same be provided. I prefer the same, however, as it is more advantageous than where the several parts are rigidly connected with each other. Where there is a loose connection in the parts, such for example as that 65 described, the controller or control-shaft 9 is

not operated from one extreme position to the other, until the planer bed has practically completed its movement in either direction, which would not be the case were all the connections rigid as in the latter event 70 the movement of the planer bed would become slower and slower until the control-shaft 9 reaches its neutral position at which point further movement of the bed would be stopped. As will be understood I provide that the controller be not shifted until the bed has practically completed its movement, at which point said controller, through the spring means, is given a rapid movement 80 from one extreme to the other whereby the driving mechanism is brought to a bed-reversing relation before the bed actually stops which as will be evident is highly advantageous in that I do not lose control of the bed at any time. 85

As I have already set forth the speed of movement of the planer bed can be governed by the position of the controller 9, the latter being oscillatory as shown. The stops can be so adjusted that the amount of movement of the controller in one direction from its neutral position, can be greater than that in the opposite direction by reason of which the speed of the planer bed will not be uniform on its two strokes or on its advance and 90 retraction.

In the construction shown the degree of movement of the controller or control-shaft 9 is regulated by limiting the movement of the swinging arm or lever 40, for example 100 by screws 45 and 46 tapped through the arms 47 and 48 of the bearing or bracket 19. The two screws can be adjusted independently so that the speed of the planer bed 3 can be different in one direction from 105 that of the other. By running in the screws the speed will be decreased while by running them outward the speed will be increased.

As the arm 24 actuated by the spring 30 through the arm 33 and rock-shaft 23 strikes 110 one or the other of the lugs 25 and 26 and carries forward the member 27 of the sleeve 28, it is desirable to limit the movement so as to keep the projections 29 and 29' in proper striking position for the dogs 18 and 115 17. For this purpose there is provided an arm 24', forming an integral part of the sleeve 28, and which is limited in its throw by the two stop screws 49 and 50 screwed through the projections 51 and 52 of the 120 bracket 19.

I may if desired and to prevent accidental movement of the parts, provide means as the spring 53 encircling the rod 54 provided at its outer end with a head 55 against which the outer end of said spring bears, said head being connected by the pivot 56 with the lever 40. The inner end of said spring bears against the collar 57 in which said rod 54 is slidably fitted, said block having a 130

pendent shank or stud swiveled in the extension 58 on the framework of the machine. Said spring as will be evident maintains the parts in their respective shifted positions.

5 Means are also provided for preventing rebound or reaction of the sleeve 28 and parts connected therewith, those shown will now be set forth. Said sleeve 28 has the enlargement 60 in which is tapped the screw 61, the bore in which said screw is fitted being plain at its inner end to receive the block or shoe 62, said bore also receiving the coiled push spring 63 bearing against said screw and shoe respectively and which tends 10 constantly to press or force said shoe against the surface of said tube 22 with a force sufficient to secure the desired object.

There may be cases where it is desirable to prevent motion of the rack bar or some 20 equivalent member, and the means shown for this purpose will now be described. Said rack bar has near its outer end on the outer edge thereof the notch or slot 64 (Figs. 8 to 11 inclusive) to receive the locking member or detent 65 shown as being in its operative or holding relation in Figs. 9 and 10 at which time its inner end is held in said notch by the spring 66 acting against said locking member the framework of the machine having a casing 67 for said locking member and spring. Said casing is slotted at 67' to receive the angle lever 68 pivoted at its angle in said slot 67', one arm of said angle lever being fitted in a lateral recess in 30 said locking member 65 and the other arm being pivoted to one extremity of the rod or link 69 pivoted at its opposite extremity to the operating lever 70 pivoted at one end on a suitable bearing on the framework. The 40 connection between said rod 69 and lever 70 is between the ends of the latter and at one side of the longitudinal center so that the lever and rod present together a toggle. In Fig. 9 the locking member 65 is shown as 45 being in working relation to prevent movement of the rack-bar 38. To release the rack-bar the lever 70 will be manipulated to draw the rod 69 to the left in said view, thereby through the angle lever withdraw-

50 ing the active portion of said locking member 65 from the notch, the movement being continued until the pivot point between the rod 69 and lever 70 has crossed the center line of the toggle which acts to lock the locking member against return movement.

55 While it is believed that the operation of the machine will be fully understood from the description thereof already given, still it is desirable to briefly refer to some features of the same. Initially the stop screws 49 and 50 are set so as to allow the sleeve 28 to turn far enough in either direction to allow the dogs 17 or 18 to pass the extension 29 or the lug 29'; and to provide for the 60 maximum movement of the control member

9. In the normal working of the mechanism the dogs would not pass these projections for the reason that the movement of the reciprocating member 2 would be reversed before the dogs could pass the parts 29 or 29'. Indeed, these two latter members would be thrown ahead of the dogs by the action of the spring 30. Under certain circumstances, however, where the movement of the reciprocating member 2 is operated by the movement of the lever 40 by hand, the dogs may be carried beyond their normal working positions. The stop screws 45 and 46 may be adjusted approximately to the to and fro speeds required. The final adjustment of these two screws, however, may be made after the mechanism is in motion, since their adjustment does not in any way interfere with the running of the mechanism, only limiting the speed of the movement in one or the other direction by limiting the throw of the lever 40.

85 The actual limits of the rotation of the rock shaft 23 are not necessarily determined by the lugs 25 and 26 and the arm 24', 90 stopped by the screws 49 and 50, but the real limits of rotation for all speeds below the maximum are determined by the stop screws 45 and 46 limiting the movement of the lever 40, the slot 42 of which limits the movement 95 of the arm 33 and thereby through the described connections, the movement of the control shaft 9.

100 The spring 53 is made lighter than the spring 30, since the spring 53 is not an operating spring except in the sense of holding the arm 40 from an accidental shifting of its position when there is no other restraining influence. The spring 53 does not therefore interfere with the action of the spring 105 30, which is strong enough to actually operate the lever 33 when once this lever is carried beyond its neutral position in either direction.

110 I desire to call attention to the fact that the variable speed gear mechanism of whatever character the same may be whether hydraulic or otherwise, is adapted to effect variations in speed from zero to a maximum progressively, that is without steps. That is 115 to say there is no interval of time ensuing when a change from one speed to another is made as is the case when the control is accomplished electrically through the intervention of a rheostat, the changes in speed 120 when a rheostat is being present, being stepped ones.

125 What I claim is:

1. The combination of a reciprocating member, driving mechanism for reciprocating said member, comprising a controller shiftable in opposite directions past a neutral position to effect the reversal of said reciprocating member, an oscillatory operating device, said reciprocating member 130
